UNITED STATES PATENT OFFICE

THOMAS H. SYMINGTON, DECEASED, LATE OF BALTIMORE, MARYLAND, BY EDITH R. SYMINGTON AND THOMAS R. SYMINGTON, EXECUTORS, OF BALTIMORE, MARYLAND, ASSIGNORS TO T. H. SYMINGTON & SON, INC., OF BALTIMORE, MARYLAND, A CORPORATION OF MARYLAND

TRUCK SIDE FRAME

Application filed November 11, 1931. Serial No. 574,434.

The invention relates to side frames for railway car trucks and has for its principal object the provision in a side frame of the integral cast steel type of a novel construction at the juncture of the compression and tension members with each other and with the journal box. 55

An important object of the invention is to provide a side frame in which the tension member, though connected with the journal box, is located an appreciable distance above the top thereof. 60

Another object is to provide a side frame in which a tie is provided joining the journal box and the web of the tension member at right angles to the latter for the purpose of transmitting transverse forces from the box to the tension member proper. 65

A further object is to provide a construction of this character in which the tension member is bifurcated beyond the point where the force transmitting tie connects it with the journal box, the web at the sides of the bifurcation being increased in thickness to 70 ward the extremity to compensate for the loss of area entailed by slotting out or bifurcating the web.

Still another object is to provide a side frame in which there is provided a plurality of ribs or webs rising from the roof of the journal box and merging into the sides of the compression member, these webs being in staggered relation to other webs extending from the roof of the box and merging into the outer faces of the compression member at 75 its juncture with the tension member.

Yet another object is to provide a side frame in which the intersection of the neutral axes of the compression and tension members may be a greater distance above the top of the journal box than is possible with the ordinary construction so that the compression member will have its outer end inclined downwardly comparatively gradually. 80

Furthermore it is an object to provide a construction of this character in which due provision is made to insure strength and rigidity and to avoid chunkiness of the metal at any point or points. 85

An additional object is to provide a side

frame possessing these meritorious characteristics and which will at the same time be as simple and no more expensive to make than one of ordinary pattern, in addition to being efficient and durable in service, and a general improvement in the art. 55

To the attainment of the foregoing and other objects and advantages, the invention preferably consists in the details of construction and the arrangement and combination of parts to be hereinafter more fully described and claimed, and illustrated in the accompanying drawing in which:

Figure 1 is a vertical longitudinal section through one-half of a side frame constructed 65 in accordance with the invention,

Figure 2 is a top plan view thereof,

Figure 3 is a fragmentary section taken on the line 3—3 of Figure 1, and

Figure 4 is a vertical cross section taken 70 on the line 4—4 of Figure 1.

Referring more particularly to the drawing there is shown one-half of a side frame, this being sufficient as both sides are identically the same. This frame comprises compression and tension members 5 and 6, respectively, converging at their outer ends and united with an integral journal box 7. At their inner portions these members are joined by column guides or pedestals 8 rising from 80 the load supporting beam 9 which provides a seat 10 adapted to form a support for the usual or any preferred spring means for supporting the truck bolster, the bolster and springs being naturally located within the window opening 85 11 defined between the spaced column guides or pedestals 8. The juncture of the lower end of each column guide with the tension member 6 is preferably reinforced and the strain taken by inclined knees 12 and a somewhat similar structure 13 is provided at the juncture with the compression member 5. Any ordinary or preferred brake hanger bracket 14 is also provided in association with the column guides. These details are de- 90

scribed for the sake of clearness and completeness of the disclosure but the invention lies in the construction at the journal box' as will be described. 95

The compression and tension members 5 100

and 6 are channel shaped in cross section with their open sides extending toward each other, these open sides being formed with stiffening beads 15 and 16, respectively. The outer end 5 portion of the compression member 5 is rounded off at 17 from a point above the center of the journal box to the outer side thereof and the top wall of the compression member is cut away or bifurcated at 18 from this 10 same point to the end, thus defining webs 19 which gradually taper off or merge into the sides adjacent the end of the compression member. The confronting portions of the compression and tension members are united 15 at a point approximately above the inner edge of the journal box and the beads 15 and 16 join at this point designated at 20. Spaced inwardly from this point the confronting sides of the compression and tension members 20 are joined by downwardly and outwardly inclined ties 21 preferably stiffened by means of ribs 22 on their inner or confronting faces.

The bottom wall of the tension member 6 25 does not run directly into the journal box but is located an appreciable distance thereabove but joined thereto by a tie 23 which is integral with the inner upper edge of the journal box and with the bottom wall or web of the 30 tension member and at right angles to the latter. Ribs 24 join the inner side wall of the journal box with the bottom wall or web of the tension member 6 for strengthening purposes. The tie 23 combined with the ribs 35 24 will act to transmit transverse forces from the box to the tension member. Beginning at the tie 23 the web or bottom wall of the tension member 6 is cut away or bifurcated at 25, thus defining webs 26 which taper off and merge 40 into the metal at the sides of the juncture of the compression and tension members. To compensate for the loss of area resulting from this bifurcation the webs 26 gradually increase in thickness as they approach and 45 merge at 27 into the metal at the juncture referred to, this point being moreover above the center of the journal box.

To stiffen the journal box roof so that it 50 will have sufficient strength and rigidity to oppose thrusts thereon, there are provided pairs of triangular webs 28 and 29 which are located at opposite sides of the longitudinal center line of the box and which merge into the roof 30 thereof and into the sides of the 55 metal at the juncture of the compression and tension members. In addition, other webs 31 are provided located outwardly of this juncture and merging into the roof of the box and into the outer sides of the metal, these 60 webs being located along the longitudinal center of the box.

The neutral axis of each column guide is indicated by the line 32 and intersects the neutral axes 33 and 34 of the compression 65 and tension members at the points 35 and

36 and the neutral axes 33 and 34 intersect at the point 37 considerably above the center of the journal box, the increase in the distance between the roof of the box and the point 37, as compared with ordinary types of structures, being brought about by the fact that the bottom wall or web of the tension member is spaced an appreciable distance above the upper inner edge of the box as shown. This arrangement makes it possible to reduce the downward inclination or pitch of the end portions of the compression member. 70 75

Another important feature is involved in the present invention, namely: the formation of the inside brass lugs of the journal box. 80

Referring to Figure 4 it will be observed that these lugs 38 have their upper ends flared laterally at 39 at their connection with the roof so as to give a uniform width to the tie 23. If this were not done there might be a tendency for the metal to be "chunky" at this particular point and as such would be highly undesirable the present expedient has been resorted to. 85 90

A side frame constructed in the manner disclosed and having the characteristics described is of course used in the same manner as any other of the same general type. However, this construction is highly advantageous in that every provision possible has been made at the juncture of the compression and tension members with each other and with the journal box to obtain the maximum strength and rigidity and consequent durability. The tie connecting the upper inner edge of the box with the bottom or web of the tension member provides an adequate thrust receiving member for taking the transverse forces transmitted from the box. 100 105

The increase in the thickness of the webs resulting from bifurcating the bottom wall of the tension member beyond the thrust transmitting tie is of considerable importance as it adequately compensates for the reduction in the width of the metal so that no strength is sacrificed as the result of the bifurcation. Moreover the employment of the two pairs of webs 28 and 29 at the roof of the box and at opposite sides of the longitudinal center thereof is of great importance as the roof is greatly strengthened. The straddling relation of these pairs of webs with respect to the single central external webs 31 is beneficial as it brings about a more uniform distribution of the strains instead of having them concentrated at any point or points. 115 120

From the foregoing description and a study of the drawing it is believed that the construction, operation and advantages will be readily apparent to one skilled in the art without further explanation. 125

While there is shown and described the preferred embodiment of the invention, it should be understood that the disclosure is 130

merely an exemplification of the principles involved as the right is reserved to make all such changes in the details of construction as will widen the field of utility and increase 5 the adaptability of the device provided such changes constitute no departure from the spirit of the invention or the scope of the claims hereunto appended.

Having thus described the invention, what 10 is claimed is:

1. In a side frame, compression and tension members converging at their outer ends and integrally joined to a journal box, the tension member being of channel shape in 15 cross section with its open side uppermost, the bottom or closed wall of said tension member being located appreciably above the inner edge of the top of the journal box and joined thereto by a thrust transmitting tie.

2. In a side frame, compression and tension members converging at their outer ends and integrally joined to a journal box, the tension member being of channel shape in cross section with its open side uppermost, 25 the bottom or closed wall of said tension member being located appreciably above the inner edge of the top of the journal box and joined thereto by a thrust transmitting tie merging directly into the corner of the journal box and located at right angles to said bottom wall of the tension member.

3. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and joined thereto by a thrust transmitting tie, and fillets located beneath and extending from said tie and joining the journal box to the bottom of the tension member.

4. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and joined thereto by a thrust transmitting tie, said bottom wall of the tension member being bifurcated beyond said tie to define webs tapering in width and merging into the sides of the juncture of the compression and tension members.

5. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and

joined thereto by a thrust transmitting tie, said bottom wall of the tension member being bifurcated beyond said tie to define webs tapering in width and merging into the sides of the juncture of the compression and tension members, said webs increasing in thickness toward their union with said juncture to compensate for the loss in area resulting from the bifurcation. 70

6. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and joined thereto by a thrust transmitting tie, said bottom wall of the tension member being bifurcated beyond said tie to define webs tapering in width and merging into the sides of the juncture of the compression and tension members, and pairs of substantially triangular webs rising from the roof of the journal box and merging into the sides of the juncture of the compression and tension members. 75 80 85

7. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and joined thereto by a thrust transmitting tie, said bottom wall of the tension member being bifurcated beyond said tie to define webs tapering in width and merging into the sides of the juncture of the compression and tension members, and pairs of substantially triangular webs rising from the roof of the journal box and merging into the sides of the juncture of the compression and tension members, said pairs of webs being located at opposite sides of the longitudinal center of the box. 90 95 100 105

8. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and joined thereto by a thrust transmitting tie, said bottom wall of the tension member being bifurcated beyond said tie to define webs tapering in width and merging into the sides of the juncture of the compression and tension members, said pairs of webs rising from the roof of the journal box and merging into the sides of the juncture of the compression and tension members, said pairs of webs rising from the roof of the box and merging into the sides of the juncture of the compression and tension members and being 110 115 120 125 130

located equidistant from the longitudinal center of the box and at opposite sides thereof.

9. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and joined thereto by a thrust transmitting tie, said bottom wall of the tension member being bifurcated beyond said tie to define webs tapering in width and merging into the sides of the juncture of the compression and tension members, pairs of substantially triangular webs rising from the roof of the journal box and merging into the sides of the juncture of the compression and tension members, the points of merging of said webs into the sides of said juncture being above the center line of the box, and pairs of webs rising from the roof of the box and merging into the sides of said juncture at opposite sides of the points where said first named webs merge thereinto.

10. In a side frame, compression and tension members converging at their outer ends and integrally joined to a journal box, the tension members being of channel shape in cross section with its open side uppermost, the bottom or closed wall of said tension member being located appreciably above the inner edge of the top of the journal box and joined thereto by a thrust transmitting tie, said bottom wall of the tension member being bifurcated beyond said tie to define webs tapering in width and merging into the sides of the juncture of the compression and tension members, pairs of substantially triangular webs rising from the roof of the journal box and merging into the sides of the juncture of the compression and tension members, said pairs of webs rising from the roof of the box and merging into the sides of the juncture of the compression and tension members and being located equi-distant from the longitudinal center of the box and at opposite sides thereof, and other webs rising from the roof of the box at the longitudinal center thereof and merging into the juncture of the tension and compression members at the outer surfaces thereof.

11. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and joined thereto by a thrust transmitting tie, said compression member curving downwardly from a point above the center of the box and being bifurcated from said point with the

edges of the bifurcation formed with webs merging into the inner faces of the sides of the juncture of the compression and tension members.

12. In a side frame, compression and tension members converging at their outer ends and joined to each other and to an integral journal box, the neutral axes of said compression and tension members intersecting at a point above the center of the box, the compression member having its outer end curved downwardly and bifurcated from said point with the sides of the bifurcation merging into the sides of the juncture of the compression and tension members, the tension member having its bottom wall extending above the upper inner corner of the box and joined thereto by a tie and ribs, the tension member being bifurcated beyond said tie to define webs merging into the sides of said juncture adjacent the points of intersection of the neutral axes.

13. In a side frame, compression and tension members converging at their outer ends and joined to each other and to an integral journal box, the neutral axes of said compression and tension members intersecting at a point above the center of the box, the compression member having its outer end curved downwardly and bifurcated from said point with the sides of the bifurcation merging into the sides of the juncture of the compression and tension members, the tension member having its bottom wall extending above the upper inner corner of the box and joined thereto by a tie and ribs, the tension member being bifurcated beyond said tie to define webs merging into the sides of said juncture adjacent the points of intersection of the neutral axes, and pairs of reinforcing webs rising from the roof of the box and merging into said juncture beneath said webs.

14. In a side frame, compression and tension members converging at their outer ends and integrally joined to a journal box, the tension member being of channel shape in cross section with its open side uppermost, the bottom or closed wall of said tension member being located appreciably above the inner edge of the top of the journal box and joined thereto by a thrust transmitting tie, the journal box having inside brass lugs flared laterally and merging into the roof at said tie.

In testimony whereof we affix our signatures.
